METHOD OF SMELTING AND INCINERATING.

1,160,509.

Specification of Letters Patent.

Patented Nov. 16, 1915.

Application filed January 13, 1913, Serial No. 741,625. Renewed April 26, 1915. Serial No. 24,157.

To all whom it may concern:

Be it known that I, WILLIAM R. HESLEWOOD, a citizen of the United States, residing at Oakland, in the county of Alameda and State of California, have invented new and useful Improvements in Methods of Smelting and Incinerating, of which the following is a specification.

This invention relates to a method and apparatus for smelting and incinerating.

It is the object of this invention to provide a process for smelting and incinerating, and a means for accomplishing same by which the use of crude petroleum and other hydrocarbons as a fuel for smelting ores and incinerating garbage and like operations, is rendered possible and practical.

A further object is to provide a method and means for smelting and incinerating by which an intense heat is evolved from a liquid or gaseous fuel, and by which a thorough action of the heat is secured throughout the diameter of the furnace and fusion zone to effect a rapid, efficient and economical reduction of the materials being worked.

Another object is to provide a method of smelting, and apparatus therefor, by which the necessity of delivering charges of fuel with the ores or other materials to be treated other than the combustibles naturally contained therein, is largely obviated and by which the freezing of the charge is rendered practically impossible during the smelting or incinerating operation.

The invention primarily resides in burning a hydrocarbon fuel on one side of a body of the materials to be smelted or incinerated, and drawing the hot gases thus generated through the materials by induced draft or suction. This method is distinguished from the well known blast system in which the heat units are forced through the body of materials being worked, by fans or blowers from the side of the body on which the heat is generated, in that the heat is drawn through the body from the side opposite the point of combustion by induced draft. The principal advantage of the present method resides in the fact, that by drawing the hot gases through the body or mass of material in the furnace by suction, an equal force is exerted throughout the whole mass, causing the heat to be distributed immediately and thoroughly therethrough, whereas, in the

blast system channels are formed in the mass by reason of the resistance offered by the mass to the passage of the blast therethrough, which channels follow the line of least resistance in the mass resulting in portions of the mass being unsubjected for a time to the direct action of the heat. Furthermore this resistance of the charge to penetration of the blast causes back firing where liquid or gaseous fuels are employed, for the reason that the penetration is slower than the combustion, thereby reducing the heating efficiency.

Another advantage resides in the fact that by drawing the heat units through the mass no cooling of the heat units is occasioned in the furnace other than what is caused by contact with the mass which is largely compensated for by the burning of combustible materials therein, whereas in the blast system the volume of air required to force a draft through the mass being greater than that necessary for combustion, a consequent reduction of temperature results; the excess volume of air required for penetration acting as a cooling agent.

The apparatus employed for carrying out the present method of smelting and incinerating is shown in the accompanying drawing in which the figure illustrates a vertical section thereof, and in which A represents a furnace of any suitable construction, preferably having a vertical shaft 2. The ores to be smelted or the materials to be incinerated are delivered to the shaft 2 at its upper end through a feed hopper 3, of any suitable construction. A crucible or hearth 4 is formed at the lower end of the furnace and a suitable draw-off 5 is provided adjacent thereto.

Formed in the walls of the furnace at any suitable point above the hearth 4 is a series of chambers 6, which are preferably conical in shape with their large ends opening to the shaft 2 and their small ends communicating with twy whole shaft 2, to prevent the melted materials descending in the shaft 2 from collecting in and choking the chambers 6.

Extending into the chambers 6 through

the twyers 7 are burners or nozzles 8 of any suitable type, by which a liquid fuel such as crude petroleum may be delivered to the interior of the chambers 6, from any suitable source of supply; valves 9 being provided for regulating the amount of fuel delivered to the chambers 6.

The chambers 6 are designed to serve as mixing and combustion chambers for the 10 liquid or gaseous fuel and air delivered thereto, in which the fuel is burned before entering the furnace shaft 2.

The upper end of the shaft 2 communicates through a series of vents 10 with a 15 water-jacketed flue or pipe 11 which leads to an ejector casing 12 formed of two bell-shaped or opposed conical sections secured together at their mouths; the pipe 11 terminating in one of the conical sections of the 20 casing 12 at a point to one side of its axis.

Projecting axially into the end of the casing 8 at the axes of the conical section to which the pipe 11 connects, and in close proximity to the open end of the latter, is a 25 nozzle 13. The nozzle 13 is connected to the discharge end of a pump 14 of any suitable description, preferably of the centrifugal type, the inlet of which is connected to a pipe 15 leading to a tank or reservoir 16, and 30 opening thereto some distance below the surface of water or other suitable liquid therein; the pump 14 being provided as a means for forcibly ejecting the liquid in the tank through the nozzle 13, at high pressure and 35 with great velocity.

The nozzle 13 discharges into an opening formed in the apex of the conical section of the casing 12 directly opposite the discharge end of the nozzle. This opening 40 leads to a divergent pipe or throat 17 which leads and opens to the interior of the tank 16 adjacent its bottom and beneath the liquid contained therein.

In carrying out the present process a 45 preliminary or initial charge of carbon in the form of coke or charcoal is placed in the furnace and ignited. The pump 14 then being set in operation, the liquid in the tank 16 will be rapidly drawn into the pipe 15 50 and discharged back into the tank through the nozzle 13, casing 12, and throat 17, thus being constantly circulated. The rapidly moving jet directed by the nozzle 13 across the chamber 12 tends to create a vacuum 55 therein by drawing the air and other gases out of the chamber 12 and ejecting them into the tank 16. This exhaustion of the air from the chamber 12 creates a suction 60 therein which acts through the pipe 11 to induce a suction or vacuum in the space in the shaft 2 above the preliminary carbon charge therein, thereby inducing a draft in the furnace. The draft induced by the ejector draws air into the furnace to support 65 the combustion of the preliminary carbon

charge which, on burning, generates an intense heat in a few moments, which radiates into the chambers 6. The liquid or gaseous fuel is then delivered to the chambers 6 through the nozzles 8, the heat from the 70 burning carbon charge vaporizing the fuel, if liquid hydrocarbon is used, and igniting the mixture of fuel and air in the chambers 6. The gradually increasing diameter of the chambers 6 allows for the expansion of 75 the heated gases therein. The induced draft draws the hot products of combustion into the furnace from the chambers 6. The furnace is then charged continuously with the materials to be treated, which vary as occasion demands; such for instance, as mineral containing ores to be smelted, or garbage to be incinerated. The primary carbon charge is employed principally as a generating means, and in some instances may be dispensed with; any other means of generation 80 may be employed. The temperature of the heat radiating into the chambers 6 from the stack, when the furnace is in operation, is great enough to maintain a continuous vaporization and combustion of the liquid fuel. 90

The pull or suction of the induced draft created by the ejector acting equally throughout the diameter of the shaft, tends to raise or lift the bodies composing the 95 charge or mass in the furnace and creates an upward suction through the interstices between the bodies in the mass which acts to draw the hot gases evolved by the burning fuel in the lower part of the furnace upward, equally and uniformly through the 100 mass.

The suction maintained in the furnace by the ejector causes air to rush through the twyers 7 to displace that burned with the 105 liquid fuel; the volume of which may be regulated by adjusting the speed of the pump 14.

By regulating the quantity of air drawn in by the suction draft and adjusting the delivery of the fuel to the chambers 6, the proper proportions for the complete combustion of the latter may be obtained, which results in a high temperature, being produced, the extent of which is proportional 115 and is limited only to the quantity of fuel burned.

The heat generated in this furnace increases in proportion to the fuel added, making it possible to generate heat in an ascending scale without any decrease at any point. The high temperature in the furnace insures a rapid combustion of the gaseous fuel in the chambers 6, and the powerful induced draft insures the hot 120 products of this combustion being impinged with great velocity on that portion of the mass in the furnace extending across its diameter on a level with the mouths of the chambers 6. This results in fusion of most 125 130

of the materials on this plane taking place instantaneously, the most refractory materials being broken down by the intense heat generated at this point. This, with the even 5 distribution of the heat units throughout the materials, being treated, results in the rapid reduction of same, which has been found in practice to exceed that possible with the ordinary blast furnace, and only obtainable 10 in an electric furnace.

The products of combustion and hot gases generated in the furnace by the fusion of the materials are drawn upward throughout the mass of materials above the fusion zone, 15 and act to effectively roast the charge; these gases being drawn off from the furnace by the ejector. The hot gases on coming in contact with the water jet in the ejector are considerably cooled, which results in a 20 reduction of their volume. This is an important feature, which adds to the efficiency of the apparatus, as the reduction of the volume of gases at this point increases the suction in the casing 12, and thereby augments the draft. The gases drawn into the 25 ejector are delivered into the tank 16 below the liquid therein, and are there further condensed and collected for further treatment.

30 It has been found in practice that the charge in the furnace which is more or less broken up, acts as no obstruction to the draft and permits of materials in a fine state of division being treated, which would choke 35 the ordinary type of furnace, and consequently result in freezing.

An important feature of this invention resides in the impossibility of the mass in the furnace congealing or freezing and consequently choking the combustion chambers 40 and twyters when the furnace is in operation, thus rendering it unnecessary to bar the twyters to keep them open; and in the ease with which a freeze can be overcome if 45 it should occur by a shut down; it having been ascertained in practice that cold iron at the mouth of the combustion chambers can be melted down in a few moments, by the impact thereon of the flames drawn from the 50 chambers 6.

It is manifest that various materials require various treatments in the furnace. For instance, in smelting sulfid ores, portions of the ore are combustible and it is therefore 55 necessary to draw more air into the furnace than is required to combust the liquid fuel in order to support the combustion of the combustible portions of the ore; the sulfids assisting in the generation of heat. In some 60 cases it may be desirable to introduce coke or charcoal to the furnace with a charge, but ordinarily this is not required. Again, where oxidization of mineral ores is desired, the oil may be temporarily cut off to allow 65 the introduction and distribution of oxygen

throughout the charge. In any event the quantity of oxygen supplied to the furnace in a unit of time can be regulated by varying the speed and volume of the jet in the ejector by adjusting the speed of the pump 70 14, or in any other manner; as the volume of air admitted through the twyters is proportional to the volume of gases drawn off by the ejector.

It is obvious that the hereinbefore described process and apparatus is applicable for use in the treatment of various ores and that it is also adapted for use in incinerating garbage or other materials. It is also apparent that various fuels may be employed, either liquid or gaseous, and that various forms of furnace construction may be resorted to as occasion demands, and that any form of suction device may be used, though the suction device shown is preferred 85 owing to its high power and efficiency.

The main feature of the construction of the apparatus resides in the combustion chambers 6, and particularly in the inclined roof thereof, and arranging these chambers 90 to one side of the main shaft in such manner that molten matter running down the walls of the shaft will drop from the upper edges of the chambers 6 into the crucible and not run back into the chambers. This 95 insures the prevention of the chambers 6 becoming choked. While the chambers 6 are here shown as separated, it is manifest that they could be connected to form one continuous annular chamber if desired.

100 It is essential to keep the chambers 6 free from obstructions and uncongested so that there will be sufficient space for the combustion of the fuel. The suction draft insures combustion taking place in the chambers 6, 105 owing to the products of combustion being immediately drawn into the furnace and a direct current established through the chambers 6. Combustion could not be supported in the chambers 6 by a forced draft owing to 110 back fire.

Combustion of the materials in the furnace is confined to a zone within the furnace, which zone is governed by the amount 115 of air admitted thereto. By confining the combustion of fuel to a zone, the materials above the combustion zone are roasted and carbonized by the heat units passing therethrough, but not consumed, because no oxygen is mixed therewith to support combustion. This feature is particularly advantageous in garbage incinerating operations, 120 in that the moisture in the garbage permits of the vegetable oils becoming volatilized without being consumed or incinerated. The top of the furnace being hermetically sealed by the liquid in the tank, prevents oxygen 125 from mixing with the hot gases, so that the carbonized gases therein will not be combusted, and no oxygen reaching the carbon 130

in the furnace the carbon can not burn until it reaches the combustion zone.

Having thus described my invention, what I claim and desire to secure by Letters Patent, is—

The herein-described smelting and incinerating method which consists in confining a mass of material, subjecting same to combustion at the base portion and, at one side thereof, then in setting up a circulatory body of water which leads from and discharges into a main body of water to form a vacuum, and then in placing the vacuum in

communication with a point above the surface of the material to cause the vacuum to draw the gases from above the surface of the material into said circulatory body of water and be discharged directly with the latter into the main body of water.

In testimony whereof I have hereunto set my hand in the presence of two subscribing witnesses.

WILLIAM R. HESLEWOOD.
